UNITED STATES PATENT OFFICE

1,974,763

PROCESS FOR THE PRODUCTION OF ROLL-GOLD STAMPING FOILS UPON PLATES OR BANDS

Karl Wirth, Berlin-Charlottenburg, Germany,
assignor to Julius A. C. Fichtmueller, Stapleton,
Staten Island, N. Y.Application July 24, 1930, Serial No. 470,254
In Germany April 2, 1930

2 Claims. (CL. 204—8)

Roll-gold stamping foils have so far been so produced in a commercial form, that known qualities, in most cases orange or lemon coloured beaten leaf gold, were employed, and the leaf gold, beaten to squares either by hand or with the aid of machines, applied to suitably prepared continuous paper of limited width in accordance with known methods in conjunction with an adhesive substance or gluten having a low melting point. 5 This process is extremely troublesome, requires highly skilled workers, specially trained to the work, and is about 50% more expensive than the beaten, unmounted leaf gold of the same size. It has been attempted, instead of employing beaten leaf gold, to produce the so-called party-gold with the aid of electrolytically produced gold deposits in conjunction with other metals, e. g. silver and the like, in accordance with known methods, and to transfer these metallic layers or 10 the gold only, also by means of adhesive substances or glutens, to suitable paper or other mounts or carriers ready to receive the foil, for instance, pergamyn paper, cellophane etc. All such endeavours, however, have not produced the desired result, owing to the fact, that the removal of the electrolytically produced layer or layers, without leaving a trace, with the aid of above-mentioned expedients requires the employment of 15 an adhesive substance or gluten of considerable adhesiveness, which, however, was the cause, that during the stamping operations proper the metallic layers did not allow of being transferred to the object to be stamped, because they adhered too strongly to the auxiliary layer or carrier, whereas 20 in conjunction with the employment of adhesive substances or glutens with lesser adhesive properties the removal of the electrolytically produced layer without leaving a trace is impossible. 25 The process in accordance with this invention 40 is based upon the idea of employing a slow combustible carrier, which renders it possible, with the aid of little or no adhesive substance or gluten at all, to remove, without leaving a trace, electrolytically produced metallic layers and 45 which, when stamping with a hot die, loses its own adhesiveness, thereby releasing, without leaving a trace, the metallic layers in form of the stamping die, which with the back of the gold foil 50 or layer being correspondingly grounded, securely adhere to the object being stamped. The carrier in accordance with this invention serves, on the one hand, as transfer medium of the metallic layer from the mount and on the other hand, 55 as carrier of the removed metallic layer and simultaneously as delivering agent of the metallic layer to the object to be stamped.

In consideration of the fact that by employing a liquid carrier considerable surface tensions are caused, rendering it possible to remove the metallic deposits without leaving a trace, e. g. as known by employing liquid gelatine, it was ascertained, that electrolytically produced deposits upon metal plates or bands for the production of roll-gold stamping foils, may be removed without leaving a trace through the medium of a liquid carrier, produced from a cellulose ester with a certain degree of acetylation which is a well known commercial product and varied by means of softening or hardening media. This renders it possible to undertake stamping operations upon a big scale, resulting in a saving of work and material. A further saving of gold is effected owing to the fact that the gold, which does not adhere to the object to be stamped, remains upon the carrier. The waste-gold, resulting from the stamping operations, may be entirely recovered, and the carrier proper, by being reduced to a liquid state, may also be employed again. 60 65 70 75 80

In the drawing the process has been represented by way of example on a considerably enlarged scale. Upon a band- or leaf-like base *a* one or more metallic layers *b* have been electrolytically deposited, upon which the liquid carrier *c*, consisting of acetylated ester, is applied. After the carrier has solidified, the layer *b*, together with the layer *c* may be removed and constitutes a roll-gold stamping foil which, after being correspondingly grounded in a known manner, may be employed for stamping purposes without any further preparation. 85 90 95 100

I claim:

1. The process for the production of rolled metal stamping foil which consists in depositing metal upon a support, covering the metal with an acetylated cellulose ester in liquid form, allowing it to solidify and mechanically separating the solidified sheet and deposited metal together from said support. 105
2. The process for the production of rolled metal stamping foil which consists in electrodepositing the metal upon a metal support, covering the deposited metal with an acetylated cellulose ester in liquid form, allowing it to solidify and mechanically separating the solidified sheet and deposited metal together from said support. 110

KARL WIRTH.
